(57) **CLAIM**

The ornamental design for a plasma monitoring flow cell, as shown and described.

DESCRIPTION

FIG. 1 is a top right perspective view of a plasma monitoring flow cell showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front left perspective view thereof;

FIG. 9 is a rear left perspective view thereof;

FIG. 10 is a cross-section view taken along line 10-10 in

FIG. 6; and,

(Continued)

FIG. 11 is a cross-section view taken along line 11-11 in FIG. 2.
